UNITED STATES PATENT OFFICE.

FREDERICK C. PAYNE, OF NEW YORK, N. Y.

CABINET-BEDSTEAD.

SPECIFICATION forming part of Letters Patent No. 279,426, dated June 12, 1883.

Application filed January 11, 1883. (No model.)

To all whom it may concern:

Be it known that I, FREDERICK C. PAYNE, a citizen of the United States, residing at New York, in the county and State of New York, 5 have invented new and useful Improvements in Cabinet-Bedsteads, of which the following is a specification.

This invention relates to a folding bedstead which, when folded, has the appearance of a cabinet. The novel and peculiar construction which forms the subject-matter of my invention is pointed out and explained in the following specification.

In the accompanying drawings, Figure 1 represents a longitudinal vertical section in the plane *x x*, Fig. 2, when the bedstead is unfolded. Fig. 2 is a horizontal section in the plane *y y*, Fig. 1. Fig. 3 is a vertical section when the bedstead is folded up. Fig. 4 is a 20 similar section on a larger scale than the previous figures.

Similar letters indicate corresponding parts.

In these drawings, the letter *A* designates the back of a cabinet. *B* is the top; *C*, the 25 base, and *D* the stationary front. This stationary front forms the support for the movable front or bed-bottom *E*, the two being connected together by hinge-joints *a*, so that the movable front or bed-bottom can be turned 30 down to the position shown in Figs. 1 and 2, or that the same can be turned up to the position shown in Fig. 3. When the bed-bottom is turned up the hinge-joints *a* are concealed by a hinged flap, *b*, and the grating which 35 forms the bed-bottom proper is concealed by a suitable drapery, *c*, formed of silk or other textile material. To the outer or open end of the bed-bottom *E* are connected the legs *F* by hinge-joints *d*, and when the bed-bottom is 40 turned down said legs drop into the position shown in Fig. 1, a stop, *e*, serving to retain them in the required position; but when the bed-bottom is turned up to the position shown in Fig. 3 the legs *F* turn down automatically, 45 so as to bear against the drapery *c* and to form ornaments for the cabinet. At the same time the stop *e* assumes the position shown in Fig. 3, thereby imparting to the cabinet a finished appearance.

50 By referring to Figs. 1 and 2 it will be seen

that the bed-bottom *E* extends beyond the inner surface of the stationary front *D*, and to the inner ends of the intermediate slats, *f f*, of said bottom is firmly secured a balance-weight, *G*, while to the inner ends of the outside slats, 55 *g g*, is connected the head-frame *H* by hinge-joints *h*, and to this head-frame is connected the head-board *I* by hinge-joints *i*.

When the bed is folded up to the position shown in Fig. 3 the head-board rests against 60 the back *A* of the cabinet, and between said head-board and the bed-bottom *E* sufficient room is left for the mattress, the sheets, the blankets, and the pillows, the head-frame *H* serving to support the bedding and to prevent 65 the same from sliding off from the bed-bottom.

When the bed-bottom is being turned down to the position shown in Figs. 1 and 2 the weight of the outer end of said bottom is balanced by the weight *G*, together with the weight of the 70 head-frame *H* and the head-board *I*; and in order to facilitate the motion of the head-frame said frame is furnished with rollers *j j*, which ride up on inclines *k k*, formed on the base of the cabinet. As the downward motion of the 75 outer end of the bed-bottom continues the head-frame assumes an upwardly-inclined position, (see Fig. 1,) in which it is retained by the contact of its inner ends with the inner ends of the slats *g g*, while the head-board *I* 80 slides up on the back *A* of the cabinet and catches behind stops *l*, fastened to the sides of said cabinet, so that it is prevented from dropping forward. By the time the bed-bottom has reached the position shown in Fig. 1 the 85 mattress and the pillow reach the position indicated in dotted lines in Fig. 1, and it requires but little time to fix up the bed.

What I claim as new, and desire to secure by Letters Patent, is—

1. The combination, with the stationary front *D*, movable front or bed-bottom *E*, and hinge-joint *a* connecting the two, of a flap, *b*, hinged or pivoted to the movable front or bed-bottom, and overhanging and concealing the 95 hinge-joint when the said front or bed-bottom is in its closed position, substantially as described.

2. The combination of the stationary front *D*, the bed-bottom *E*, hinged thereto, and com- 100

posed of outside slats, *g g*, and intermediate slats, *ff*, with a weight, *G*, carried by and moving with the inner ends of the intermediate slats, the head-frame *H*, hinged to the outside 5 slats, and the head-board *I*, hinged to the head-frame, substantially as described.

3: The combination, substantially as hereinbefore described, of the stationary front *D*, the bed-bottom *E*, connected to said stationary front by hinge-joints, the balance-weight 10 *G*, the head-frame *H*, hinged to the inner end

of the bed-bottom and carrying a hinged head-board, the rollers *j j* on said head-frame, and the inclines *k k* on the base *C*.

In testimony whereof I have hereunto set 15 my hand and seal in the presence of two subscribing witnesses.

FREDERICK C. PAYNE. [L. S.]
